UNITED STATES PATENT OFFICE.

RICKASON STILWELL, OF NEW YORK, N. Y., ASSIGNOR, BY DIRECT AND MESNE ASSIGNMENTS, TO BRADFORD WILLARD AND EMELINE C. STILWELL, BOTH OF SAME PLACE.

MEANS FOR APPLYING ELECTRICAL OR GALVANIC CURRENTS TO BEDS, COUCHES, &c.

SPECIFICATION forming part of Letters Patent No. 285,853, dated October 2, 1883.

Application filed March 15, 1883. (No model.)

To all whom it may concern:

Be it known that I, RICKASON STILWELL, of the city, county, and State of New York, have invented certain Improvements in Means for Applying Electrical or Galvanic Currents to Beds, Couches, Mattresses and the like, of which the following is a specification.

In the application of electricity to beds, mattresses, couches, and the like, it has heretofore been considered necessary to incorporate the electrical conductors and their adjuncts with the bed, couch, or mattress itself, thereby rendering such appliances comparatively expensive and beyond the reach of a large portion of the community.

The object of my invention is to provide an apparatus whereby electricity may be applied to sleepers, in connection with the use of any ordinary bed, couch, or mattress, thereby saving the expense of the bed, couch, or mattress itself, and limiting the expense to that incidental to the apparatus immediately employed in the application of electricity to the person.

My invention comprises a novel means whereby this object is secured.

Figure 1 is a plan view, and Fig. 2 a transverse sectional view, of an apparatus constructed according to my said invention.

A is a metallic-wire frame-work composed of wire, copper, or other suitable metal arranged in substantially the relation shown in Fig. 1—that is to say, in such manner as to form meshes of greater or less diameter, which in practice may vary within wide limits, but which may be stated as, say, three inches in width, more or less. This frame-work is designed to be laid on any ordinary or suitable bed, mattress, or couch, and to have electrical currents transmitted through substantially its entire extent. In order to provide for this, one end of the said frame-work is connected by one or more wires, preferably by several, as represented at *a* in Fig. 1, with a circuit-wire, *B*, which connects with one of the poles of the battery *C*—as, for example, the positive pole thereof. These wires may be insulated by an india-rubber or other appro-

priate coating, when desired, in order that the currents may not be diverted therefrom by accidental contact with conductors of electricity. In like manner the opposite end of the said frame is provided with one or more wires, (indicated at *b*.) which connect with a circuit-wire, *D*, which in its turn is connected with one of the poles—as, for example, the positive pole—of the battery. This circuit-wire should be insulated in such manner as to avoid the divergence of currents therefrom by accidental or other contact with conducting substances. It will be observed that the current of the battery being established, the said current, assuming the apparatus to be properly proportioned, (this latter is a matter of mere workshop skill,) will pass through the whole of the frame-work in a continuous current proportioned to the intensity and uniformity of the action of the battery. The frame-work, being laid upon the surface of a mattress, bed, or couch, *C*, as shown in Fig. 2, either above or below the blankets or sheets thereof, will cause the passage of the current of electricity in due proximity to the body of the person lying thereon, and it will effect in said person the curative or hygienic results known to be experienced from the application of electricity.

It is to be understood that any of the usual or known equivalents for galvanic batteries may be substituted in place of the battery to produce the requisite electrical currents through the circuit-wires, and consequently through the frame.

What I claim as my invention is—

As a new article of manufacture, a metallic-wire frame provided with circuit-wires, whereby it may be connected with a galvanic battery or other source of electricity, the said frame being so proportioned that it may be placed upon a bed, mattress, or couch, all substantially as and for the purpose herein set forth.

RICKASON STILWELL.
